(57) **CLAIM**

The ornamental design for a fastening clip for cables, as shown and described.

DESCRIPTION

FIG. 1 is an isometric view showing the left side and top of our design of a fastening clip for cables.

FIG. 2 is an isometric view showing the right side and bottom of the fastening clip for cables of FIG. 1.

FIG. 3 is a front elevational view of the fastening clip for cables of FIGS. 1 and 2.

FIG. 4 is a rear elevational view of the fastening clip for cables of FIGS. 1-3.

FIG. 5 is a left side elevational view of the fastening clip for cables of FIGS. 1-4.

FIG. 6 is a right side elevational view of the fastening clip for cables of FIGS. 1-5.

FIG. 7 is a top plan view of the fastening clip for cables of FIGS. 1-6; and,

FIG. 8 is a bottom view of the fastening clip for cables of FIGS. 1-7.

1 Claim, 8 Drawing Sheets
